UNITED STATES PATENT OFFICE.

JOHN L. WELLER AND FRANKLIN EARL WINCHESTER, OF RICHMOND, INDIANA.

LOCKING DEVICE FOR INTERNAL-COMBUSTION ENGINES.

1,329,943.

Specification of Letters Patent.

Patented Feb. 3, 1920.

Application filed April 7, 1917. Serial No. 160,426.

To all whom it may concern:

Be it known that we, JOHN L. WELLER and FRANKLIN EARL WINCHESTER, citizens of the United States, residing at Richmond, 5 in the county of Wayne and State of Indiana, have invented certain new and useful Improvements in Locking Devices for Internal-Combustion Engines, of which the following is a specification.

10 This invention relates to improvements in locking devices for internal combustion engines, it more particularly relating to devices especially adapted for locking the motor of an automobile although not necessarily limited to that particular purpose.

15 The object of the invention is to provide a lock for the fuel supply which is incorporated as a self-contained or unitary part of the carbureter so that the locking feature 20 may be installed by the builder of the car or by the maker of a carbureter in a manner to obviate the necessity of altering the construction of the motor or its manifold or otherwise disturbing the arrangement and 25 relative positions of the manifold and carbureter.

30 A further object of the invention is to provide a locking device of the character referred to which will be simple in construction and effective in operation.

In the accompanying drawings:—

35 Figure 1 is a side elevation of a carbureter partly broken away and shown in section with a portion of the manifold in section showing our improved locking device applied thereto, the parts being shown in locked position.

Fig. 2 is a detailed section of a portion of the locking devices.

40 Fig. 3 is a view of the key.

Fig. 4 is a section showing the parts in the unlocked position.

45 Referring to the drawings, 1 represents the casing of a carbureter which may be of any well known type, the upper portion of the casing being provided with the usual fuel outlet controlled by the usual butterfly valve 6, which is capable of being rotated from the position shown in Fig. 1 only in a 50 clockwise direction. In the present case, the wall of the carbureter adjacent the outlet is provided with an enlargement 1^a, bored out to form a chamber 1^b within which is located a cylindrical casing 2 containing any suitable form of operating devices for the purpose of retracting and ejecting a pin 3,

which device will be controlled by a key 8. This pin 3, when the parts are in the locking position shown in Fig. 1, enters a recess 4 in the wall of the enlarged portion 1^a 60 and thereby locks the cylindrical casing 2. The casing 2 has integrally formed therewith a locking bolt 2^a which projects through an opening in the wall of the carbureter casing which leads into the outlet 65 passage thereof just beneath the butterfly valve, 6, when in its closed position. A coiled spring 5 is interposed between the inner end of the casing 2 and the inner wall of the chamber 1^b which normally tends to 70 throw the casing 1 and locking bolt 2^a to unlocking position. The casing 2 is provided with a slot or recess 2^c and a set-screw 7 threaded into the wall of the enlarged portion 1^a projects into this recess 75 so as to limit the movement of the casing 2 in either direction.

80 In operation, assuming the butterfly valve to be locked as shown in Fig. 1, the operator by inserting the key 8 is enabled to withdraw the pin 3 from the recess 4, whereupon the spring 5 throws the casing 2 and its locking bolt 2^a outwardly to unlocking position, this outward movement being limited by the set-screw 7 in the slot 2^c. When it is 85 desired to lock the butterfly valve 6, the casing 2 is pushed inwardly until the pin 3 registers with the recess 4, which will be the case when the inward movement of the casing 2 is stopped by the set screw 7, whereupon the pin 3 is thrown into the recess 4 and the parts thereby locked including the valve 6. In the present case the pin 3 is thrown to locking position by a spring (not shown), although, if desired, the key may 90 be employed to not only withdraw the pin but also to throw it to locking position.

95 By the construction described it will be seen that it will be possible to equip an automobile with a locking device which will be 100 effective and which will also obviate the necessity of altering or disturbing any of the fixed parts, as would be the case where a valve and lock is attempted to be inserted in the manifold between the carbureter 105 proper and the engine. This construction is also particularly applicable to the later types of automobiles in which the manifold is practically eliminated, thereby precluding the possibility of successfully installing 110 a lockable valve therein. The construction also is of value in that it enables the maker

of a carbureter to successfully equip the carbureter with a locking device more economically and effectively than where such locking device is installed as an accessory in the manifold or between the carbureter and the manifold. The construction is also such that the locking devices, when in unlocked position, will form no obstruction in the manifold or carbureter.

10 There has been shown in the drawing but a small portion of the manifold pipe, indicated by the reference character 9, to which the carbureter is attached.

Having thus described our invention, we

15 claim:

1. In a device of the character described, a carbureter and its casing, a valve permanently secured within said casing an insertible locking member for said valve slidably mounted within the casing of the carbureter comprising solely a sliding locking bolt and a casing member yieldingly mount-

ed within the carbureter casing, said locking bolt being controlled by a key substantially as specified.

2. In a device of the character described, a carbureter and its casing, a valve permanently secured within said casing an insertible lock comprising solely a slidably mounted locking bolt and casing together with a spring for holding same in unlocked position and a locking pin, said locking bolt being arranged transversely within the casing of the carbureter whereby the locking bolt will contact with the side of said

permanently secured valve for the purpose specified.

In testimony whereof, we have hereunto

set our hands this 31st day of March, 1917

JOHN L. WELLER.

FRANKLIN EARL WINCHESTER.
